UNITED STATES PATENT OFFICE.

OSCAR L. AABY, OF WOODVILLE, WISCONSIN.

STOVEPIPE ANCHOR.

Application filed January 21, 1926. Serial No. 82,690.

This invention relates to stove pipe anchors, and more particularly to improvements in the stove pipe anchor forming the subject-matter of my copending application, filed January 31, 1925, and serially numbered 6,147. The stove pipe anchor shown in that application embodies a rod positioned in the chimney and contacting with a wall thereof, a band secured to the stove pipe, and straps connected to the band and having loops for the reception of the rod. In that structure, the straps are provided with half-twists in order to permit the loops to be arranged for the reception of the rod, and the provision of the straps with half-twists is necessary for the reason that the rod is straight.

The present invention has for one of its objects to improve and simplify the structure described to the end that it will not be necessary to provide the straps with half-twists and to establish such a connection between the rod and straps as to render it impossible for the latter to become casually disengaged from the former, and this object is attained by providing the rod with angular portions and engaging the looped ends of the straps with such portions.

With the foregoing and other objects in view, the invention consists of the novel construction, combination and arrangement of parts hereinafter fully described and claimed, and illustrated in the accompanying drawing, wherein:

Figure 1 is a view in side elevation illustrating the application of a stove pipe anchor embodying the present invention,

Figure 2 is a sectional view taken on the plane indicated by the line 2—2 of Figure 1,

Figure 3 is a view in end elevation of the applied stove pipe anchor,

Figure 4 is a detail sectional view taken on the plane indicated by the line 4—4 of Figure 1, and

Figures 5 and 6 are detail views illustrating the manner in which the sections of the band are detachably connected together.

Corresponding and like parts are referred to in the following description, and designated in the several views of the accompanying drawing, by similar reference characters.

In the drawing, 1 designates a fragmentary portion of a chimney, 2 a thimble secured within the stove pipe receiving open-

ing of the chimney, and 3 a fragmentary portion of a stove pipe having an end positioned in the thimble.

The anchor comprises a rod 4, straps 5, and a band 6. The rod 4, which is positioned in the chimney 1, extends across the thimble 2 and contacts with the inner end thereof. The rod 4 comprises a body portion 4^a which has a diametrical arrangement with respect to the thimble 2, angular portions 4^b which extend in opposite directions from the ends of the body portion 4^a and are substantially parallel, and terminal portions 4^c which extend upwardly from the angular portions 4^b. The straps 5 are provided with looped inner ends 5^a which embrace or engage with the rod portions 4^b, and are provided with tongues 5^b which are relatively spaced and two of which are engaged with the band 6. The band 6 encircles the stove pipe 3, and is preferably of sectional formation. The sections 6^a of the band 6 are provided with slots 6^b to permit them to be interengaged in the manner shown in Figures 5 and 6. The band sections 6^a are also provided with ears 6^c for the reception of a retaining bolt 7.

The provision of the rod 4 with the angular portions 4^b permits the straps 5 to be connected to the rod 4 and extended along opposite sides of the stove pipe 3 without providing them with half-twists. Furthermore, the manner in which the straps 5 are connected to the rod 4 prevents the latter from becoming accidentally detached from the former. After the rod 4 and straps 5 have been applied, an end of the stove pipe 3 is inserted in the thimble 2, the band 6 is then applied to the stove pipe 3 and engaged with a tongue 5^b of each strap 5, and the bolt 7 is thence applied to secure the band 6 in place.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. A stove pipe anchor comprising a rod adapted to be positioned in a chimney across the stove pipe receiving opening thereof and provided with angular portions, straps connected to the angular portions of the rod,

and an element for securing the straps to the stove pipe.

2. A stove pipe anchor comprising a rod adapted to be positioned in a chimney across the stove pipe receiving opening thereof and provided with oppositely directed angular portions, straps connected to the angular portions of the rod, and an element for securing the straps to the stove pipe.

3. A stove pipe anchor comprising a rod 10 adapted to be positioned in a chimney across the stove pipe receiving opening thereof and provided intermediate its ends with parallel portions, straps connected to the angular portions of the rod, and an element for securing the straps to the stove pipe. 15

In testimony whereof I affix my signature.
OSCAR L. AABY.
